(57) **CLAIM**

The ornamental design for a travel tray for kids toddler car seat, as shown and described.

DESCRIPTION

FIG. 1 is a top, rear and right side perspective view of a travel tray for kids toddler car seat showing my new design; FIG. 2 is a bottom, front and left side perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a rear elevational view thereof.

The broken lines show the portions of the travel tray for kids toddler car seat that form no part of the claimed design.

1 Claim, 8 Drawing Sheets
